MECHANISM FOR DRAWING TEXTILE
SLIVERS OR ROVINGSJohn Frederick Jackson, Pawtucket, R. I., assignor
to H & B American Machine Company, a cor-
poration of Maine

Application June 15, 1937, Serial No. 148,329

3 Claims. (Cl. 19—131)

This invention relates to drawing mechanisms for textile slivers or rovings; and has for one of its objects the provision of an improved construction of drafting apparatus utilizing belts or aprons in which each of the individual aprons or belts employed for supporting and conducting the strand of sliver or roving from one pair of feed rolls to another, are of an endless construction.

10 Another object of the invention is to provide simple and improved means for guiding the belts whereby they may be easily removed and renewed at will without interfering with the normal operation of the rest of the machine or of necessitating stoppage of the complete machine with the consequent loss of production and expense which has heretofore been the case during use of the prior art belt mechanisms employing belts or aprons the ends of which are cemented together after being put in place.

15 Another object of the invention is to provide a removable construction of drafting mechanism whereby the assembly of belts and associated rotatable driving members may be removed as a complete unit from the frame of the machine.

20 Another object is to provide a device of the above character in which the driving rolls for the belts and the front guide elements over which the forward runs of the belts extend are each supported at their ends solely on the usual cap bars of the frame of the machine.

Another object of the invention is to provide a unit assembly of belts and driving members which is completely devoid of any mechanism 25 requiring attachment to or in embracing relation completely about a fixed driving roll on the machine.

Another object of the invention is to provide a construction having a plurality of upper and 30 lower endless belts wherein the rotatable members for driving the lower belts have positive but detachable driving connection with a separate exterior driving member.

Another object of the invention is to provide 35 a plurality of sets of endless belts, each set having cooperating runs between which the sliver or roving travels in which the arrangement is such that one of the rotatable members for driving one of the belts of each set has positive driving connection with an exterior continuous 40 fixed drive shaft underlying the rotatable member.

Another object of the invention is to provide a 45 conveying mechanism for the fibers of a removable unit construction in which the guide ele-

ments and rotatable members for the endless belts are insertable in the loops of the aprons or belts and encircled thereby, whereby the belts serve solely to maintain the parts in assembly when the unit is removed from the machine.

5 A further object of the invention is to provide a construction for a mechanism of the above character in which the rotatable member and the guide elements for the forward loop of the belts are guided and supported independently 10 of one another at their ends in cap bars which act to locate the unit in operating relation with reference to a driving member having positive driving connection with the lower of the rotatable members and also serve to stiffen the 15 assembly of belts and rolls and to position the latter and the belt guides in proper operating relation.

With these and other objects in view, the invention consists of certain novel features of construction, as will be more fully described, and particularly pointed out in the appended claims.

20 In the accompanying drawings:

Fig. 1 is a perspective view of one form of unit drafting mechanism embodying the present invention;

Fig. 2 is a vertical sectional view looking at the end of the drafting rolls, and showing the roll stand in which they are mounted and showing my invention applied thereto;

Fig. 3 is a front sectional view taken longitudinally on the line 3—3 of Fig. 2, showing in full lines the rotatable driving members for the belts and the main driving roll therefor and the manner in which the latter drives the belts;

Fig. 4 is a front longitudinal sectional view taken on the line 4—4 of Fig. 2;

Fig. 5 is a vertical sectional view taken on the line 5—5 of Fig. 4;

Fig. 6 is a perspective view of one of the guide bars for a pair of belts;

Fig. 7 is a perspective view of the top belt roll of the drafting unit;

Fig. 8 is a perspective view of the bottom belt roll of the drafting unit and showing the driving means therefor; and

Fig. 9 is a fragmentary perspective view of a modified form of support member for the belt guide bars.

Heretofore, the belts or aprons employed in the prior art drafting mechanisms have been usually guided between side plates or flanges of a frame or cradle in which the driving rolls for the belts are mounted, side plates for confining the belts being rigidly joined together by longitudi-

nally arranged rods and guide bars to provide a unitary structure. This frame or cradle, furthermore, is commonly provided with a pair of detachable bars or rods mounted in spaced relation at its forward portion and over which the front loops of the belts are guided in close proximity to the drawing rolls. However, in the machines employing this prior art construction the lower roller about which the bottom belt runs has usually consisted of a continuous roll extending the length of the machine, this roll being made up of a series of sections rigidly joined together at their ends for driving connection. The upper roll usually is short and mounted directly above the bottom sectional roll and formed with a pair of spaced cylindrical belt engaging portions, this roll being removably supported in the usual cap bars, and consequently may be readily lifted therefrom to permit insertion in the loop of the upper belt which thus may be initially made endless. Owing to the great length and continuous construction of the lower roll around which the bottom belt runs, it is, however, impossible to use in this location a previously fabricated apron or belt of endless construction, thus making it necessary during each replacement of the belt to cement the ends of the belt in place after wrapping the strip of belting around its respective guide bar and this bottom roll, which process requires stopping of the complete machine with the consequent loss of production; and in order to provide an improved construction of drafting apparatus of the belt type which does not depend upon such cemented belts and to improve and simplify such drawing mechanisms, I have provided a construction utilizing a pair of endless belts between which the sliver or roving travels wherein each of said belts is arranged in an encircling relation about a rotatable driving member or cylinder and a guide element in which the rotatable driving member and the guide element for each belt are supported solely at their ends on a part of the frame of the machine; and to this end, I preferably employ the usual cap bars for this purpose wherein I have provided therein a series of spaced vertical channels formed in their opposite side faces thereof which have interfitting engagement with the ends of the rotatable driving member and the guide elements for the belts for guiding and supporting the same and to locate the parts in predetermined spaced relation; and I have further provided a construction in which the driving members and the guide elements for the belts are maintained in assembled operating relation solely by the belts and thus may be removed bodily from the frame of the machine as a unit; and furthermore, I have found it to be of advantage to construct the guide elements for the belts as a unitary structure and comprising a pair of similar guide bar elements each having spaced recessed portions or channels formed therein for receiving and guiding the side edges of the belts in which the bars are arranged back to back and with their grooved portions facing outwardly in opposite directions and suitably spaced for accommodating the free encircling movement of the belts; and the following is a more detailed description of the present embodiment of this invention, illustrating the preferred means by which these advantageous results may be accomplished:

With reference to the drawings, 10 designates one of a series of spaced roll stands which are of well known construction in the art, each hav-

ing a standard 11 provided with a suitable base portion (not shown) whereby each of the stands may be rigidly mounted on a suitable support of the frame of the machine. As shown in Fig. 1 the roll stand 10 is provided with a top platform member 12 having its forward end extending upwardly to form the usual journal for the front bottom drawing roll 13. At the rear of each of the roll stands and on the platform 12 is adjustably secured a bearing block 15 on which is journaled the usual bottom back roll 16. The rolls 13 and 16 may be formed either with a smooth cylindrical outer surface or of a fluted construction, as desired. This block 15 is formed at its bottom with a suitable longitudinally extending channel for interfitting seating engagement with a cooperating tongue portion on the upper face portion of the platform 12 of the roll stand, as is the usual construction in the art. The forward portion of this block 15 is of reduced thickness and at the rear of this portion is a bolt 17 the lower end of which extends through a slot 18 formed in the platform 12 of each roll stand, and having a nut 19 threaded thereon and engaging at its upper end the lower face of the platform 12, as is well known construction in the art, for permitting adjustment of the block 15 and the lower back roll 16 towards and from the lower front roll 13.

The rolls 13 and 16 are each of a sectional construction in which a plurality of short sections are keyed together at their ends to provide a continuous elongated shaft which is journaled at a plurality of intervals in the roll stands and extending the entire length of the machine, as usual, the rolls being positively driven at different speeds by suitable gearing (not shown) at the end of the machine, at rates whereby the draft on the yarn, sliver or roving between the successive rolls is increased. The rolls 13 and 16 are each preferably formed with fluted portions 20 and 21 respectively, at intervals along their length, such portions being alternately arranged in spaced relation with smooth cylindrical hub portions (not shown) of a lesser diameter therebetween, as is the common construction in the art.

A driving roll 24 also in the form of a single continuous shaft of similar elongated sectional construction as the lower rolls 13 and 16 and extending the entire length of the machine, is provided at intervals with a plurality of spaced bearing portions 25 which are journaled in the forward reduced portion of the block 15 in the roll stands. By loosening the nut 19, the rolls 16 and 24 being journaled in the common bearing block 15 thus may be moved with the block and simultaneously positioned at desired adjusted distances toward or from the lower front roll 13. Positioned on the driving roll 24 between the successive bearing portions 25 and at spaced intervals therealong are a plurality of collars 28 which, as shown in Fig. 3, form rest or support members for purposes which will hereinafter be described. Located at intervals on the driving roll 24 and between a pair of collars 28 is positioned an enlarged fluted hub portion or gear 29 and employed for purposes to presently appear, the diameter of this gear being greater than the diameter of the collars 28. This gear and the collars 28 may each be formed integral with the shaft of the roll 24 or they may comprise separate parts which are fixed in position on the roll. As shown in Fig. 2, the driving roll 24 is located below the line of travel of the sliver or roving, 75

which is designated at **S** by the dot and dash lines so as to be tangent to the peripheries of the fluted portions **20** and **21** of the lower rolls **13** and **16** respectively, and the arrangement is such as to permit my particular belt mechanism, which will presently be described and embodying the present invention, to be mounted above the driving roll **24** and in a superposed cooperating relation thereto without changing the relationship **10** of the line of travel of the yarn, as indicated by the broken line **S**, whereby the latter may travel between the cooperating surfaces of a pair of juxtaposed belts of my intermediate belt unit.

As shown in Fig. 2 of the drawings, the block **15** has a rearward extension **30** thereon in which is mounted a pivot rod **31** to which may be fixed, as by set screws **32**, a plurality of cap bars **33**. Ordinarily, there are more cap bars than roll stands, a cap bar being provided for each roll stand **10** and others being positioned intermediate of the stands, the bars being arranged for forward pivotal swinging movement over the rolls **13** and **16**. As illustrated, each cap bar **33** is of extensible construction, it being formed of two sections **34** and **35**, and connected by a telescoping rod **36**. The rear section **34** is shown as being provided with oppositely disposed vertically arranged channels or slots **37** having open ends at the top face of the cap bar and extending **30** downwardly therefrom for loosely receiving trunnions or journals **38** at the ends of the rear upper rolls **40**. The channels **37** may be provided as a deep cut in the top face of the arms **33** or in the opposite side faces thereof as separate channels extending inwardly from the sides of the cap bar arm, in which latter case they extend in a vertical direction throughout the entire depth of the arms. Similarly, the front section **35** is provided with oppositely disposed vertically arranged slots **41** positionable above the lower roll **13** and forming guides for loosely receiving the trunnions or journals **42** of the front top rolls **43**, the rolls **40** and **43** being formed with usual spaced sections (not shown) which are customarily provided with a leather or cork outer covering and adapted to rest upon the underlying fluted sections **20** and **21** of the bottom rolls **13** and **16** respectively. The above described parts have been shown in their conventional arrangement without the usual weighted saddle means for weighting the upper rolls **40** and **43** and maintaining them in place, as is well known in the art, such means forming no particular feature of the present invention. At a **55** point intermediate these channels **37** and **41** the cap bar **33** is thickened as at **45** to provide a lug which extends downwardly into close proximity to the lower drive member **24**, and formed in this lug **45** are oppositely disposed vertical channels **46** to extend throughout the entire depth thereof at a location above and substantially in vertical alignment with the axis of the driving roll **24**. A forward extension **47** which extends from the lower front portion of the thickened section **45** is provided with oppositely disposed vertical slots or channels **48** and they may extend downwardly thereof throughout either the entire portion of its depth or short of the bottom to provide a bottom flange or ledge portion **49** at the lower end of the respective channels, as shown in Fig. 4 of the drawings, for purposes to presently appear. These channels **46** and **48** form guides in which ride and are loosely supported the trunnions of the front belt **50** guide members and the belt driving rolls of my

drawing mechanisms, as will be presently more fully described.

As illustrated in the drawings, there is shown disposed between the usual drawing rolls of a long draft machine for drawing-out the sliver or roving a drawing mechanism constructed in accordance with the present invention, which comprises a pair of endless belts or aprons **51** and **52** positioned on and encircling a pair of rotatable driving cylinders or rolls **54** and **55** respectively, each of which belts receives and has insertable within its loop its respective driving roll while the forward end of the belts **51** and **52** are positioned about and run over a pair of guide bars **57** and **58** respectively. The rolls **54** and **55** are provided with trunnions or journals **60** and **61** respectively, which are adapted to loosely ride in and be removably mounted for sliding and rotary movement in the vertical slots **46** formed in the oppositely disposed faces of adjacent cap bars **33**. The upper roll **54** is an idler and is provided with a pair of spaced belt-driving sections or cylinders **62** and **63**, and an intermediate hub section **64** of reduced diameter, said sections **62** and **63** each being formed at their ends with **25** cylindrical portions **65** between which lies an intermediate portion **66** which is provided with a roughened surface formed either by knurling, milling or fluting the same. Similarly, the lower belt driving roll **55**, which is the driven roll **30** and positively driven from the roll **24**, is provided with spaced belt driving sections or cylinders **67** and **68** each of which have cylindrical end sections **69** between which is formed a roughened or knurled intermediate belt gripping portion **35**. Between the belt driving sections **67** and **68** the roll **55** has a driving hub or gear **71** which is substantially of the same diameter as that of the belt driving sections **67** and **68** and adapted to intermesh with and have positive driving connection with the driving gear **29** on the lower continuous driving roll **24** when the belt mechanism assembly is mounted as a unit in proper operating position in place in the machine, as will be hereinafter described.

As illustrated in Fig. 4, each of the belt guide bars **57** and **58** are of similar construction and each consists of a bar formed of suitable metal or other rigid, hard and smooth material, the bars **57** and **58** being arranged back to back and securely held in fixed superposed spaced relationship by means of suitable spacing collars or separators **73** and bolts **74** to provide a unitary structure. The spacing between the bars **57** and **58** always should be, however, substantially greater **55** than the thickness of the two belts **51** and **52** so as to accommodate the regular passage of the fibers of sliver or roving without preventing functioning of the belts. Each of the belt guide bars **57** and **58** has trunnions or journals **75** at **60** its ends to loosely fit in the slots **48** of the cap bar extension **47**. Formed intermediate of the bars **57** and **58** are a pair of spaced recessed portions or channels **77** and **78** which extend cross-wise of the bars, the channels in the upper bar **65** **57** extending rearwardly and downwardly from the front and top faces respectively, while those in the lower bar **58** are arranged so as to extend inwardly from the front and the bottom face of that bar. These channels **77** and **78** thus **70** formed serve to provide guides in which run the front loop of the top and bottom endless belts **51** and **52** respectively, the channels being so shaped as to provide a deep cut-out portion having substantial side walls which form flanges **75**

for guiding the side edges of the belts and for maintaining the latter in properly aligned relation with reference to the belt driving sections 62, 63 and 67, 68 of the rolls 54 and 55 respectively. The bottom surface of the channels 71 and 78 may be of suitable shape, as desired, but as illustrated in Fig. 6 it is shown as being curved so as to provide a smooth rounded front edge over which the inner circumferential surface of the belt loops run.

As shown in Figs. 1 and 4, each of the bars 57 and 58 is of the same length as the belt driving rolls 54 and 55 and thus enable the positioning of the mechanism as a unit intermediately between the sets of drawing rolls 13, 43 and 16, 40 (see Fig. 2). When so mounted, the rolls 54 and 55 will have their trunnions 60 and 61 positioned in the channels 46 of the opposed cap bars for rotation therein and thus are located in a superposed relation directly over the lower driving roll 24. The trunnions 75 of the guide bars 57 and 58 thus will be positioned in the channels 48, the trunnions 75 of the lower bar member 58 being seated or supported at their lower face by the oppositely disposed flanges 49 of a pair of adjacent cap bars 33, in which positions the recessed portions or channels 71 and 78 of the bar members 57 and 58 will be vertically aligned opposite the belt driving sections 67 and 68 of the lower driving roll 55. The pairs of endless belts or aprons 51 and 52 are positioned in an encircling relation about the roughened sections 66 and 70 of the belt driving rolls 54 and 55 respectively, and the guide bars 57 and 58 so that the lower portion of the belt 45 is positioned above and travels in a direction substantially parallel to the upper run of the lower belt 46 to cooperate therewith. Thus, the roll 55 which drives the lower belt 52 is positively driven from the driving roll 24 to cause movement of the fibers of the sliver or roving to travel between the cooperating opposed surfaces of the belts 51 and 52, whereby the movement of the sliver will in turn impart movement of the upper belt 51 in the same direction. As shown in Fig. 3 the driving roll 24 is provided with reduced portions 80 which serve to provide sufficient clearance between the driving roll 24 and the outer surface of the bottom portion of the lower belts 52 so as to permit the latter to run clear and out of contact with the driving roll 24. In accordance with this arrangement, the spaced smooth cylindrical portions 69 at each end of the belt driving cylinders 67 and 68 rest upon and are supported by the cylindrical outer surface of the spaced collars 28 of the main driving roll 24 in a floating manner, the collars also act to provide spaced flanges at each side of the bottom belts 52 to confine and guide the side edges of the latter.

As illustrated, the blocks 15 may be adjusted as desired relative to the roller stands 10 in order to position the forward loop portions of the belts 51 and 52 at desired distances in relation to the bight of the front rolls 13 and 35 respectively. In accordance with the above construction, the guide bars 57 and 58 being rigidly secured to one another, provide a unitary structure about which the forward loops of the belts 51 and 52 are fulcrumed and since they have inserted in their respective rear loops the driving rolls 54 and 55 the belts act to maintain the complete assembly together as a single unit, when removed out of operating position from the recesses of the cap bars 33, as for the purpose of effecting removal or replacement of one or more of the belts.

It will thus be apparent that in accordance

with this invention the "floating" construction of feeding apron unit thus provided is simple and inexpensive to manufacture and one which is capable of easy insertion in the frame of the machine and adapted for ready removal therefrom as a unit, whereby the belts, driving rollers therefor and guide elements may be withdrawn as a complete assembly to permit the belts to be utilized and applied in an endless manner. The construction which is provided by the present invention also enables the operator to readily replace one or more belts at will without interfering with the operation of other conveying units on the machine and without requiring the stopping of the machine for making such belt replacements since it is merely necessary to remove the weighting mechanism in the usual manner and lift out the unit assembly of bars 57 and 58, belt attached rolls 54 and 55, then slide out the rolls from the loops of the respective belts, to free the rear loops of the belts and then remove the belts by slipping them endwise over the free and unsupported outer ends of the bars 57 and 58. A fresh endless belt may be positioned in the guide frame by merely reversing the steps just described. Thus, it becomes unnecessary to piece up or cement any belt in position on the machine which has heretofore been required particularly in the replacement of the bottom belts in the previous belt devices in common use in spinning frames.

It will, of course, be understood that while I have illustrated in Fig. 2 of the drawings only one belt device embodying my invention and positioned intermediately between two sets of nip rolls that a series of such belt devices may be employed if desired in mechanisms having a plurality of successive draft stages in one or more of which an apron or belt device constructed in accordance with the present invention as above described may be inserted between the sets of nip rolls of one or all of such draft stages thereof, as desired, without departing from the spirit and scope of my invention.

In Fig. 9, another arrangement for holding the guide bars 57 and 58 and the rolls 54 and 55 is shown, in which an effective adjustment of the guide bars 57 and 58 is provided for in order to permit tightening of the belts should they become slack or stretched during use. Referring to this figure, it will be seen that the block 90 is provided with a slotted opening extending laterally of and completely through the body of the block to provide the channels or slots 92 in opposite side faces of the block for receiving the trunnions 75 of the guide bars. The channels 92 are shown as having open ends at their top portions and extend downwardly therefrom to unite with the end portions of the body opening. The bottom wall 93 of the block 90 provides a ledge portion at the lower end of each of the channels 92 on which the trunnion 75 of the lower guide bar 58 may be seated and supported.

Intermediate of the channels 92 is a bar member 95 which connects the front and back walls of the cored block and bridges the upper portion of the latter. The bar 95 is provided with a suitable bore for receiving the rod 36 on which the block 90 is supported and to which the block may be suitably clamped as by means of a screw 96 passing through and threaded into a suitable opening in the bar 95. Thus, the block 90 may be adjusted relative to each of the cap bar sections 34 and 35 respectively, and also in various positions of adjustment with respect to

bight of the front set of rolls 13 and 43, as desired.

The foregoing description is directed solely towards the construction illustrated, but I desire it to be understood that I reserve the privilege of resorting to all the mechanical changes to which the device is susceptible, the invention being defined and limited only by the terms of the appended claims.

10 I claim:

1. In a drawing mechanism for textile slivers or rovings, two sets of upper and lower drawing rolls, a guide frame for the upper roll of each set of drawing rolls, a drive shaft positioned intermediate of said sets of drawing rolls and below the plane passing through the line of nip of each of said sets of rolls, and a feeding and conveying mechanism for sliver or roving positioned between said sets of rolls and removably mounted as a unit on said guide frame, said conveying mechanism comprising a pair of guide bars positioned one above the other in spaced relation and rigidly connected at their mid-portions to form a unitary structure, said bars each having at least two spaced recesses, an endless belt in each of said recesses, the forward loop of each of said belts extending over and encircling said bars, a roll loosely inserted in the rear loop of each belt and removably mounted on centers on said guide frame, said belts having closely adjacent and substantially parallel runs for acting on the sliver or roving and also serving to maintain said guide bars and belt rolls in assembly when said conveying mechanism is removed as a unit from said frame.

2. In a drawing mechanism for textile slivers or rovings, the combination of two sets of drawing rolls, upper and lower removable rotatable cylinders positioned between said sets of drawing rolls, endless belts about and passing be-

tween said cylinders and arranged in cooperating relation thereon and between which the sliver or roving travels, each of said belts having a run extending forwardly towards the bight of one set of drawing rolls, a guide member for each of said belts and over which the end of the forward run of one of the belts extends, and means adjustable relative to said drawing rolls and said cylinders for supporting said guide member independently of said rotatable driving cylinders for the belts, said belt guide members being integrally connected together and removably mounted as a unit on said means.

3. In a drafting mechanism for textile slivers or rovings, a pair of cap bars in spaced relation to each other, drawing rolls thereon including a short bottom roll and a short top roll, said top and bottom rolls extending between said cap bars and being removably and rotatably supported thereon, an endless belt on said top roll, an endless belt on said bottom roll, a support between said cap bars for guiding internally the front loops of said belts comprising a pair of spaced bars positioned one above the other in parallel relation and fixed together at a point intermediate their ends to form a rigid unitary structure having their remote ends free, said bars being removably and non-rotatably supported at their ends alone on said cap bars, said upper and lower bars being located in front of and parallel to said top and bottom rolls respectively in the normal operating position of the bars on said cap bars, said belts being permanently endless and serving to maintain the guide bars and the driving rolls in assembled relationship when removed from the drawing mechanism and also to form a unitary demountable feeding mechanism bodily insertible into and removable from said drawing mechanism as a unit.

JOHN FREDERICK JACKSON.
